GAS MASK

Armand V. Motsinger, Aberdeen, Md.

Application February 10, 1937, Serial No. 125,082

7 Claims. (Cl. 128—141)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a gas mask and more particularly to a military gas mask having an air purifying canister supported on one shoulder of the wearer.

One object of this invention is to so support 10 the air purifying canister that it is comfortable, does not interfere with body movements, does not pull on the gas mask facepiece to thus allow leakage around the edges, and is readily adjustable to position when the mask is put on.

15 Various other objects of the invention will be understood from the following description, claims and drawing wherein.

Fig. 1 is a perspective view of the mask and canister in position.

20 Fig. 2 is a perspective view from the left side.

Fig. 3 is a front view of the casting for connecting the inlet tube and outlet valve to the gas mask.

Fig. 4 is a perspective view of the canister.

25 Referring to the drawing, the gas mask facepiece 1 has eyepieces 2 therein and web straps 3 secured thereto to hold the facepiece on the head of the wearer, each strap having a buckle for adjusting tension. Straps 3 are preferably elastic webbing to maintain the facepiece pressed 30 in airtight engagement with the face of the wearer.

35 Positioned centrally of the facepiece adjacent the nose and mouth of the wearer is a metal casting 4 having a downwardly curved outlet 5 to which an exhalation flutter valve 6 is secured. Casting 4 also has an integral inlet nipple 7 which is curved downwardly and to one side and has secured thereto a corrugated rubber hose 8. 40 Hose 8 is connected to an air purifying canister 9 which is cylindrical and has an air inlet opening 11 in one end.

45 Canister 9 contains the necessary chemicals and filter to extract poisonous and irritating 50 dusts and gases from the air. The canister is adapted to rest lightly upon the left shoulder of the wearer, thus relieving the facepiece of any strain due to the weight of the canister and is maintained in position by two elastic straps 12 and 13 secured to lugs 15 on the side of the canister. Strap 12 is connected to the facepiece 1 to the right of the casting 4, and strap 13 passes around the back of the neck of the wearer and is connected to the facepiece at the lower cheek 55 portion, as seen in Fig. 2. Strap 13 is provided

with a separable catch 14 whereby it can be easily unhooked for removal. An adjustable buckle is provided on each strap 12 and 13 so the canister can be correctly and comfortably positioned. The canister is attached to the straps 5 12 and 13 by means of lugs 15 on the canister.

With the shoulder position, the weight of the canister is carried in a natural position on the shoulder and the canister slides lightly on the shoulder when the head is turned. The adjustable elastic straps prevent excessive movement of the canister, and also tend to hold the facepiece against the face and to make it more gas-tight. This position of the canister allows the use of a short hose 8, thus minimizing the possibility of 15 snagging when the wearer is advancing through underbrush; also this position allows fording a stream without immersion of the canister.

When the canister is carried under the arm, as is common in prior practice, the canister may 20 swing forward to a position in front of the wearer when he is falling prone; also when the wearer rolls over he must roll over the canister. The shoulder position avoids these difficulties, which is an important consideration for a soldier. 25

Furthermore, the packing of the facepiece and canister is facilitated by this arrangement due to the short hose, there is less resistance to air flow, the weight is less than prior constructions, with decreased cost. Also in packing, the shoulder positioned canister may be readily slipped into 30 the facepiece to thus function as a faceform and prevent distortion of the facepiece.

The above and other advantages follow from the construction herein shown and described. It 35 will be understood that this invention is not confined to the precise details of construction herein shown for purposes of illustration, as various changes may be made without departing from the spirit of the invention or exceeding the scope 40 of the appended claims.

I claim:

1. A gas mask comprising a facepiece, means to hold the facepiece in engagement with the face of a wearer, and an air-purifying canister, said 45 canister being connected to the facepiece at separated points and adapted to rest upon the shoulder of the wearer.

2. A gas mask comprising a facepiece, means to hold the facepiece in engagement with the face 50 of a wearer, and an air-purifying canister, said canister having two flexible straps secured thereto, said straps being connected to the facepiece at opposite cheek portions, one strap adapted to pass around the back of the wearer's neck, 55

whereby said canister may rest upon the wearer's shoulder.

3. A gas mask comprising a facepiece, means to hold the facepiece in engagement with the face of a wearer, and an air-purifying canister, said canister adapted to be supported upon one shoulder of the wearer, and being retained in position by two flexible straps secured to the facepiece and canister, said straps being so arranged and secured that the pull thereof on the facepiece causes the rim of the facepiece to engage the face in a gas-tight manner.

4. The invention as defined in claim 3, wherein said straps are of elastic material.

5. The invention as defined in claim 3, wherein one of said straps has a quick detachable fastener whereby the facepiece may be readily put on and removed.

6. A gas mask comprising a facepiece, means to hold the facepiece in engagement with the face of a wearer, and an air-purifying canister, said canister being positioned to one side of the facepiece and adapted to rest on the wearer's shoulder, said canister having two elastic straps secured thereto, one strap secured to the adjacent portion of the facepiece, the other strap adapted to pass around the back of the neck and secured to the facepiece at the lower cheek portion, and means to adjust the length of each strap.

7. The invention as defined in claim 6, wherein the strap adapted to pass around the back of the neck has a readily separable fastener therein.

ARMAND V. MOTSINGER.
